(57) **CLAIM**

I claim the ornamental design for a light, as shown and described.

DESCRIPTION

FIG. 1 is a front perspective view of a light showing my ornamental design;

FIG. 2 is a front view of a light showing my ornamental design;

FIG. 3 is a rear view of a light showing my ornamental design;

FIG. 4 is a right side view of a light showing my ornamental design;

FIG. 5 is a left side view of a light showing my ornamental design;

FIG. 6 is a top view of a light showing my ornamental design;

FIG. 7 is a bottom view of a light showing my ornamental design; and,

FIG. 8 is a perspective view of the light shown in an alternative configuration of use showing the light separated for clarity of disclosure.

The broken lines in the drawings depict portions of the light that form no part of the claimed design.
